ATTORNEY

UNITED STATES PATENT OFFICE.

ROBERT E. POINDEXTER, OF INDIANAPOLIS, INDIANA.

SAW-HANDLE.

SPECIFICATION forming part of Letters Patent No. 292,946, dated February 5, 1884.
Application filed June 29, 1883. (No model.)

To all whom it may concern:

Be it known that I, ROBERT E. POINDEXTER, of the city of Indianapolis, county of Marion, and State of Indiana, have invented 5 certain new and useful Improvements in Saw-Handles, of which the following is a specification.

My said invention consists in an improved means of attaching handles to crosscut-saws, whereby the handle may be firmly and securely attached to the saw, and quickly and easily detached, as will be hereinafter more particularly described.

Referring to the accompanying drawings, which are made a part hereof, and on which similar letters of reference indicate similar parts, Figure 1 is a side elevation of one end of a saw embodying my invention; Fig. 2, an elevation of the other side of the same; Fig. 3, a longitudinal section on an enlarged scale on the dotted line $z z$; Fig. 4, a transverse vertical section on the dotted line $y y$; Fig. 5, a transverse vertical section on the dotted line $x x$, and Fig. 6 a top or plan view of the portions shown by Fig. 3.

In said drawings, the portions marked A represent the saw-blade, B the handle, and C C² the two parts of the fastening for attaching the handle to the saw.

The saw-blade A is of any desired construction, and is provided with holes a at each end.

The handle B is an ordinary saw-handle, and is provided with a hole near its lower end, over which a washer, b , should be placed.

The fastening for connecting the saw-blade and handle together is composed of the device C and the combined hook and wedge bolt C². The part C is formed to fit onto the front side of the handle, and is itself divided into two portions, one of which, c , abuts against the end of the saw at one point, and then extends out alongside said end, past the hole a therein, and is slotted or bifurcated, so as to leave said hole uncovered. The other portion, c' , of this part C extends out on the other side of the saw, (see Figs. 3 and 6,) and forms a side bearing for the wedge-shaped end of the bolt C². The bolt part C² is provided with a projection, c^2 , at one end, which enters the hole a , thus making the device a hook-bolt, and is enlarged at the same end which bears the projection c^2 , thus making it also a wedge-bolt. The stem or bolt portion

proper passes through the handle, is threaded, 55 and bears upon its end the thumb-nut c^3 .

The operation of my said invention is as follows: The projection c^2 on the bolt part C² is first inserted in the hole a in the saw-blade. The part C is then placed on the bolt portion of the part C², and slipped up close against the saw, the bifurcated end of the side c passing astride the point of the projection c^2 . The handle B is then also placed on the bolt part C², and then the nut c^3 . Said nut is 65 finally screwed tightly against the washer b on said handle, and the fastening of the handle to the saw-blade is completed. By reason of the wedge formation of the bolt part C² and the bearing c therefor, the drawing back 70 of said part C² by the thumb-nut c^3 also serves to force said part tightly against the side of the saw-blade, and thus clamps said saw-blade firmly between said part and the portion c of the part C. The several parts are 75 thus secured firmly and rigidly together. In changing or removing the handle the thumb-nut c^3 is first loosened or removed, as the case may be, when all the other parts become loose at once, and can be handled as desired. 80

Having thus fully described my said invention, what I claim as new, and desire to secure by Letters Patent, is—

1. The combination, with the saw A and handle B, of the fastening composed of the 85 combined hook and wedge bolt C² and the device C, which, together with said bolt, is adapted to clamp and hold the saw-blade, substantially as set forth.

2. The combination of the saw A, handle 90 B, device C', and hook-bolt C², provided with thumb-nut c^3 , substantially as set forth.

3. The combination, with the saw A and handle B, of the device C', having portion c extending out on one side of the saw, and 95 bifurcated to pass the projection c^2 , and the portion c' extending out on the other side of the saw, to form a bearing for the wedge-bolt, and the combined wedge and hook bolt C², having projection c^2 and thumb-nut c^3 , substantially as shown and specified.

In witness whereof I have hereunto set my hand and seal at Indianapolis, Indiana, this 26th day of June, A. D. 1883.

ROBERT E. POINDEXTER. [L. S.]

In presence of—

C. BRADFORD,
E. W. BRADFORD.
